UNITED STATES PATENT OFFICE

166,528

TABLE STAND OR SIMILAR ARTICLE

Helen D. Cole, New York, N. Y.

Application January 29, 1952, Serial No. 18,290

Term of patent 14 years

(Cl. D44—24)

To all whom it may concern:

Be it known that I, Helen D. Cole, a citizen of the United States, residing at 136 East 64th Street, New York, New York, have invented a new, original, and ornamental Design for a Table Stand or Similar Article, of which the following is a specification, reference being had to the accompanying drawing, forming part thereof, in which:

Fig. 1 is a perspective view of a table stand or similar article, showing my new design; and Fig. 2 is a top plan view thereof.

I claim:

The ornamental design for a table stand or similar article, as shown.

HELEN D. COLE.
